UNITED STATES PATENT OFFICE

156,562

GLASS HOLDING COASTER

Gerald C. Robinson, Batavia, Ill., assignor to
Girard Manufacturing Products, Inc., May-
wood, Ill., a corporation of Illinois

Application April 7, 1948, Serial No. 145,579

Term of patent 7 years

(Cl. D44--10)

To all whom it may concern:

Be it known that I, Gerald C. Robinson, a citizen of the United States, residing at Batavia, in the county of Kane and State of Illinois, have invented a new, original, and ornamental Design for a Glass Holding Coaster, of which the following is a specification, reference being had to the accompanying drawing forming part thereof.

In the drawing:

Fig. 1 is a top view of the glass holding coaster showing my new design;

Fig. 2 is a bottom view thereof; and

Fig. 3 is a cross-sectional view.

I claim:

The ornamental design for a glass holding coaster, substantially as shown.

GERALD C. ROBINSON.
